UNITED STATES PATENT OFFICE

168,136

BABY INCUBATOR

Gordon Armstrong and John W. Dorsak, Cleveland, Ohio, assignors to The Gordon Armstrong Company, Inc., Cleveland, Ohio, a corporation of Ohio

Application November 13, 1951, Serial No. 17,367

Term of patent 14 years

(Cl. D83—1)

To all whom it may concern:

Be it known that we, Gordon Armstrong and John W. Dorsak, citizens of the United States of America and residing at Cleveland, Ohio, have invented a new, original, and ornamental Design for a Baby Incubator, of which the following is a specification, reference being had to the accompanying drawings, forming a part hereof.

Fig. 1 is a perspective view of a baby incubator embodying our new design.

Fig. 2 is an enlarged sectional detail view of one of the two reflector members disposed near the center of the right front panel in Fig. 1.

The lining on the right front panel represents a contrasting colored area.

The dominant features of our design reside in the portion shown in full line.

We claim:

The ornamental design for a baby incubator, as shown and described.

GORDON ARMSTRONG.
JOHN W. DORSAK.
